REFRIGERANT COMPRESSOR

William D. Drysdale, Mount Clemens, Mich., assignor to Walter J. Sugden, Boston, Mass.

Application November 1, 1934, Serial No. 750,982

4 Claims. (Cl. 230—58)

This invention relates to refrigerant compressors and is more particularly concerned with motor compressors of the so-called "sealed unit" type in which the motor and the gas pump are contained in a sealed housing. The present invention deals with the construction and relative arrangement of the housing, the motor, the driving shaft, the bearing for the latter and the pump. The objects are to provide for an interchangeable mounting of pumps of different capacities to suit various conditions without change of the other elements and to provide for the convenient assembly and alignment of the motor and the shaft bearing.

The invention will best be understood by reference to the following description when taken in connection with the accompanying drawings of one specific embodiment thereof, while its scope will be pointed out more particularly in the appended claims.

In the drawings:

Fig. 1 is a horizontal, sectional view of a refrigerant compressor embodying the invention;

Fig. 2 is an end elevation of the same with the cover removed and with a portion of the pump shown in vertical section; and

Fig. 3 is a sectional view on line 3—3 of Fig. 2.

Referring to the drawings and to the embodiment of the invention illustrated therein, there is shown a refrigerant compressor comprising a housing 5, herein of generally cylindrical form, having one end permanently closed by an integral head 7 and the other by a cover 9. The housing may conveniently be in the form of a drawn steel shell.

Suitably secured as by welding to the internal, circumferential surface of the housing and extending inwardly therefrom, is an abutment 11 which plays an important part in the mounting of the entire mechanism in the housing. Next in order comes an electric motor comprising a rotor 13 and a stator 15, the latter having secured thereto as by welding a band 17 which in effect is a part of the stator. The external surface of this band engages the internal, circumferential surface of the housing and thus predetermines the position of the axis of the stator. One end of the band engages the abutment 11 endwise and the abutment therefore predetermines the position of the band lengthwise of the axis.

Next in order is a bearing 19 whose external surface engages the internal, circumferential surface of the housing, and thus the axis of the bearing is aligned with the axis of the stator.

One end of this bearing engages the adjacent end of the band 17 and thus the position of the bearing lengthwise of the axis is predetermined. The bearing and the band (in effect a part of the stator) are secured to each other and to the housing as by two long screws 21 which extend through the bearing through the openings 23 provided in the stator and into the abutment 11, into which the screws are threaded. The screws are provided at their outer ends with heads 25 by means of which they may be turned to clamp the bearing and the band endwise against each other and against the abutment. The whole structure may be dismounted from the housing simply by the removal of these screws.

The next in order is the pump which, as shown in Figs. 2 and 3, comprises a cylinder 27 having a piston 29 working therein, said cylinder, as shown, having a lateral intake port 31 which is covered and uncovered by the piston and which is at all times in communication with a chamber 33 into which the gaseous refrigerant enters through an inlet 35. In this example the piston is reciprocated by a connecting rod 37 whose upper end is connected to the piston by a wrist-pin 39 and whose lower end is connected to a crankpin 41 which is carried by a shaft 43. This shaft (see Fig. 1) turns in a boss 45 presented by the bearing 19, and to this shaft the rotor is suitably secured as by a key 47 and a nut 49, the latter having screw-threaded engagement with a reduced portion 51 of the shaft. The cylinder is provided with a head 53 having therein a chamber 55 in which is a plate 57 provided with openings 59 to which the gas under the compression of the piston lifts a valve 61 from a seat 63 in opposition to spring 65, the gas passing thence through an outlet 67 to a pipe 69 which leads to the exterior of the housing.

The cylinder, as shown, is provided with two lateral extensions or arms 71 which engage the adjacent end face of the bearing 19 and are clamped against the latter as by cap screws 73, the removal of which enables the pump to be dismounted without disturbing the bearing or the motor. Thus it is possible easily to change the capacity of the compressor by the substitution of cylinders and pistons of different diameters. This construction has several other advantages. It provides a better manufacturing and assembling job than in prior constructions wherein the cylinder and main bearing are in one piece. It is possible to remove the cylinder, connecting rod, piston and cylinder head without removing the

main bearing and the motor. If there is any defect in the cylinder, it is unnecessary to replace anything but the cylinder itself. The same is true of replacement because of wear. The 5 most important of these considerations, however, is the ability to obtain different displacement capacities for the pump by changing cylinders and pistons.

Having thus described one embodiment of the 10 invention, but without limiting myself thereto, what I claim and desire by Letters Patent to secure is:

1. A motor-compressor unit comprising, in combination, a housing having an internal, circumferential surface and an internal abutment extending inwardly from said surface, a motor housed within said housing and comprising a rotor and a stator, a band about and supporting said stator and having one end engaging said 15 abutment, the external surface of said band engaging said internal, circumferential surface, a bearing housed within said housing and having one end engaging the other end of said band, the external surface of said bearing engaging said 20 internal, circumferential surface, fastening elements extending through said bearing and through said stator within said band and having screw-threaded engagement with said abutment, a cylinder engaging the other end of said bearing, means by which said cylinder is detachably 25 secured to said bearing, a piston working in said cylinder, a shaft turning in said bearing and secured to and driven by said rotor, and means presenting a driving connection between said piston and said shaft.

2. A motor compressor unit comprising, in combination, a housing having a closed end and having an opposite end provided with an opening normally closed by a cover, a motor comprising a 30 rotor and a stator housed within said housing, a shaft extending through said rotor and provided with a shoulder and with a screw-thread adjacent said closed end, a nut threaded onto said screw-thread and cooperating with said shoulder 35 to secure said rotor to said shaft, a bearing for said shaft housed within said housing, a compressor housed within said housing and having a connection with said shaft constructed for connection with and disconnection from said shaft without disturbing said shaft, securing means to secure 40 said compressor to said bearing, said securing means being accessible through said opening

to attach said compressor to and to detach the same from said bearing without disturbing said bearing, and means to secure said bearing to said stator and to secure said stator to said housing.

3. A motor-compressor unit comprising, in combination, a housing presenting an abutment at one end and having an opening at its opposite end closed by a cover, a motor, a bearing, and a compressor housed within said housing and serially arranged endwise in the order named with said 5 motor adjacent said abutment and with said compressor adjacent said cover, said motor comprising a rotor and a stator, a shaft mounted in said bearing and secured to said rotor, said shaft and said compressor being supported by said bearing independently of said cover, driving means between said compressor and said shaft constructed and arranged for connecting said compressor with and disconnecting the same from said shaft without disturbing said shaft or said bearing, securing means to secure said compressor to said bearing, said securing means being accessible through said opening to attach said compressor to and to detach the same from said bearing without disturbing said bearing, and means to secure 10 said bearing endwise to said stator and to secure said stator to said abutment.

4. A motor-compressor unit comprising, in combination, a housing having a closed end and having an opposite end provided with an opening normally closed by a cover, a motor comprising a 15 rotor and a stator housed within said housing, a shaft extending through said rotor and provided with a shoulder and with a screw-thread adjacent said closed end, a nut threaded onto said 20 screw-thread and cooperating with said shoulder to secure said rotor to said shaft, a bearing for said shaft housed within said housing, a compressor housed within said housing and having a connection with said shaft constructed for connection with and disconnection from said shaft without disturbing said shaft, securing means including at least one screw having a head accessible through said opening and having a shank threaded into said bearing to attach said compressor to 25 and to detach the same from said bearing without disturbing said bearing, said shaft being supported by said bearing independently of said cover, and means to secure said bearing to said stator and to secure said stator to said housing.
